US00D929351S

(12) **United States Design Patent** (10) **Patent No.:** **US D929,351 S**
(45) **Date of Patent:** **** Aug. 31, 2021**

(54) **ACTUATOR**

(71) Applicant: **Foster Electric Company, Limited,**
Akishima (JP)

(72) Inventor: **Ryo Takahashi**, Akishima (JP)

(73) Assignee: **FOSTER ELECTRIC COMPANY,**
LIMITED, Tokyo (JP)

(**) Term: **15 Years**

(21) Appl. No.: **29/705,303**

(22) Filed: **Sep. 11, 2019**

(30) **Foreign Application Priority Data**

Mar. 28, 2019 (JP) 2019-006689

(51) **LOC (13) Cl.** **13-03**

(52) **U.S. Cl.**

USPC **D13/174**; D14/222

(58) **Field of Classification Search**

(57) **CLAIM**

The ornamental design for an actuator, as shown and described.

DESCRIPTION

FIG. 1 is a front perspective view of an actuator, showing the new design;

FIG. 2 is a rear perspective view thereof;

FIG. 3 is a front view thereof;

FIG. 4 is a rear view thereof;

FIG. 5 is a side view thereof;

FIG. 6 is a side view thereof, opposite that of FIG. 5;

FIG. 7 is another side view thereof; and,

FIG. 8 is a side view thereof, opposite that of FIG. 7.

1 Claim, 8 Drawing Sheets
